Des. 240,032
Patented May 25, 1976

240,032

WRITING INSTRUMENT OF THE MARKING TYPE

Francine Gomez, Paris, France, assignor to
Waterman S.A., Paris, France

Filed June 19, 1974, Ser. No. 480,629

Term of patent 14 years

Int. Cl. D19—06

U.S. Cl. D19—49

FIG. 1

FIG. 2

FIG. 3

FIG. 4

FIG. 1 is a perspective view of a writing instrument of the marking type showing my new design;

FIG. 2 is a front elevational view;

FIG. 3 is an exploded right side elevational view, the body portion having the same appearance around the circumference thereof; and

FIG. 4 is a bottom plan view of the body portion of the writing instrument of the marking type.

I claim:

The ornamental design for a writing instrument of the marking type, as shown and described.
